R. H. WILSON
BY Munro & Co.

ATTORNEYS

UNITED STATES PATENT OFFICE.

RAY H. WILSON, OF NEW HOLLAND, ILLINOIS.

PLOW.

1,427,141.

Specification of Letters Patent. Patented Aug. 29, 1922.

Application filed March 16, 1921. Serial No. 452,833.

To all whom it may concern:

Be it known that I, RAY H. WILSON, a citizen of the United States, and a resident of New Holland, in the county of Logan 5 and State of Illinois, have invented a new and useful Improvement in Plows, of which the following is a full, clear, and exact description.

My invention relates to improvements in 10 plows, and it consists in the combinations, constructions and arrangements herein described and claimed.

An object of my invention is to provide 15 a novel form of plow having means for preventing the accumulation of adhesive soil on the moldboard thereof.

A further object of my invention is to provide in a device of the type described a moldboard having a fixed frame and a movable 20 body portion.

A further object of my invention is to provide a device of the type described that is relatively simple in construction and operation, not likely to get out of order easily, 25 and thoroughly practical commercially.

A further object of my invention is to provide a device of the type described in which the movable portion of the moldboard may be replaced cheaply and readily when worn 30 out in service.

Other objects and advantages will appear in the following specification, and the novel features of the invention will be particularly pointed out in the appended claim.

My invention is illustrated in the accompanying drawings, forming part of this application, in which

Fig. 1 is a perspective view of the device,

Fig. 2 is a plan view of the same,

Fig. 3 is a rear view of the device,

Fig. 4 is a section through the moldboard of the device, and,

Fig. 5 is an enlarged detail view of a fragmentary portion of the moldboard.

In the usual form of plow, the share, moldboard, and landside portions thereof are relatively immovable. Certain kinds of soil are very adhesive, particularly when wet, and stick to the moldboard so that the progress of the plow through the soil is impeded and increased power is required to draw the plow. Furthermore, the soil cannot be tilled properly when the adhesive soil has accumulated on the moldboard and a given 55 amount of work can be accomplished in any manner only with great difficulty and with

a loss in time and labor, this being particularly true when the ordinary walking plow drawn by draft animals is used. When my improved device is used, soil of any nature 60 will be turned up uniformly and evenly so that the land is properly tilled.

In carrying out my invention, I provide a share 1 that is made of any suitable material, such as steel or chilled cast iron, and is 65 curved in the conventional manner. The share 1 has the usual cutting edges and is joined to the usual landside 2 that is bolted or otherwise rigidly secured at 3 to a plate 4 secured at 5 to a beam 6. The parts described so far are ordinary in construction and form no part of my invention except in so far as they cooperate with the parts about to be described.

I now provide a pair of curved moldboard 75 frame members 7 and 8 having the form best seen in Figures 1 and 4 and being made of any suitable material, preferably metal. The frame member 7 is rigidly secured, as at 9, at its lower end to the upper edge portion 80 of the share 1 adjacent to the rear end thereof. The frame member 8 is rigidly secured, as at 10, to the upper edge portion of the share 1 adjacent to the forward or cutting edge of the latter, as shown in Fig. 1, and 85 to the beam 6 by means of a connector 11 so that the frame members 7 and 8 are parallel with one another. A transversely extending roller 12 has co-axially alined studs or stub shafts 13 projecting from its ends 90 and journaled in the frame members 7 and 8 adjacent to the lower ends of the latter so that the roller 12 will turn freely. A similar roller 14 is provided with projecting studs or shafts 15 journaled in slots 16 95 in the frame members 7 and 8 adjacent to the upper ends thereof. The roller 14 is parallel with the roller 12 and can be adjusted in position relative thereto by operating adjusting screws 17 that are disposed in threaded openings 18 in the upper end walls of the frame members 7 and 8 and have their ends engaging with the studs or shafts 15.

An endless belt or apron 19 that is formed 105 of any suitable material, such as canvass or a like strong flexible material, is passed around the rollers 12 and 14 and is guided in its movement by a plurality of transversely extending spaced apart slats 20 110 which are secured to the inner side of the apron 19 and have their ends projecting be-

yond the corresponding ends of the apron for slidable movement along guide grooves 21-21 in the adjacent side walls of the frame members 7 and 8 adjacent their upper sides and along guide shoulders 22-22 defined by longitudinal recesses 23-23 in the under sides of the frame members 7 and 8.

From the foregoing description of the various parts of the device, the operation thereof may be readily understood. The soil cut by the share 1 will be guided upwardly into contact with the movable apron 19, which will be moved by such contact and will lay the turned up soil in even laps so that the plowed land is properly prepared for further tilling. On account of the movement of the apron 19, the frictional resistance on account of the contact of the soil with the moldboard is reduced to a minimum and consequently my device can be drawn more easily than an ordinary plow in performing a given work.

Obviously, the movement of the apron 19 will prevent the accumulation of soil on the moldboard as occurs when an ordinary plow is used and so detrimentally affects the operation of the latter.

I preferably provide a transverse brace 24 secured at 25 to the frame member 7 and at 26 to the landside so that the device embodying my invention is sufficiently rigid for use under ordinary service conditions.

When the apron 19 becomes worn, it may be readily replaced.

Obviously, many adaptations and modifications of the form of the device other than that illustrated in the accompanying drawings may be provided without departing from the spirit and scope of my invention as disclosed in the foregoing specification and outlined more particularly in the appended claim, and I therefore consider such modifications and adaptations as my own.

I claim:

In a plow, a pair of parallel moldboard frame members, each having a rigid connection at its lower end with the upper edge portion of the plow share, said frame members being fashioned with parallel longitudinally extending guide grooves in their inner faces adjacent to the upper edge thereof and with longitudinally extending guide shoulders offset outwardly from their inner faces along the lower edges thereof, a pair of transversely disposed parallel rollers rotatably supported between the frame members adjacent to the upper and lower ends thereof, an endless apron passed around said rollers, and spaced transverse slats secured to the inner side of said apron and arranged with their opposite ends in position to slidably engage the said guide grooves and in sliding contact with the inner faces of said guide shoulders.

RAY H. WILSON.
